Specification of Letters Patent.

Patented Dec. 9, 1919.

Application filed July 25, 1914, Serial No. 853,017. Renewed December 5, 1917. Serial No. 205,664.

To all whom it may concern:

Be it known that I, HARVEY D. WILLIAMS, a citizen of the United States, residing in the town of Wallingford, in the county of 5 New Haven and State of Connecticut, have invented certain new and useful Improvements in Gearing, of which the following is a specification.

This invention relates to that class of 10 toothed gearing in which the wheel member of a pair of gears, has the teeth thereof angularly-disposed relatively to a line that is normal to the plane of revolution and is parallel to the axis of revolution of such 15 wheel.

The present application is in part a continuation of my application filed April 14, 1913, Serial No. 760,861, on which was issued Letters Patent No. 1,112,509, dated October 6, 1914, for improvements in bevel gearing.

A principal object of the invention is to furnish a system of toothed-gearing, in which a pair of the gears comprises a wheel 25 having the working-surfaces of its teeth conforming to a single-reproduction configuration, and a mating pinion having the work-surfaces of its teeth conforming to a coacting compound-reproduction configuration; thus the teeth of the gear-wheel and 30 the teeth of the mating pinion therefor are of dissimilar formation, or configuration.

A further object is to furnish such gearing in which the profiles-pairs (through the 35 length of the tooth-surfaces of the wheel) are uniform in relation to a geometric master-form-axis and are also uniform in relation to a geometric plane in which said master-form-axis is located, as hereinafter more 40 fully explained.

A further object of my present invention is to furnish an improved toothed-gearing of that class in which the longitudinal line or geometrical axis of each pair of adjacent 45 tooth-surfaces is disposed or located in an angular relation to the axis of revolution, as in certain kinds of bevel and skew-bevel, and in skew-spur gears; also to furnish such gearing in which the "wheel", in the pair 50 of gears shall constitute a master-wheel adapted for operating correctly not only with pinions of varying diameters but also with such pinions located with their axes in various degrees of divergence or axial skew, 55 respectively, from an axial-plane radial to

the master-wheel axis, and also relatively to the plane of rotation of the wheel. In this system of gearing, therefore, one skew-tooth master-wheel may be practically and successfully employed in mesh with pinions 60 of different diameters and having their axes of revolution located in different planes, respectively.

Another object is to furnish pairs of gears having superior operative features within a 65 range of proportions which will include the larger classes of such gears, and thus utilize to the advantage of a large number of cases, certain features not equally applicable to the whole range of gear-wheel proportions. Accordingly, while my present improvements may not be suitable or well adapted for use in gear wheels of some proportions and sizes,—as regards, for instance, the pitch-circles and the relative numbers 70 and sizes of the teeth,—this restriction in the range of applicability may be considered as a means for securing desirable and important advantages in the mode of operation and in the manufacture of classes of 75 gearing which are commercially of much greater importance.

In my improved toothed-gearing, I provide the "wheel",—which will usually be the larger member of the pair,—with working faces of a form adapted to be readily precisioned, and I then arrange these working-surfaces in a longitudinal parallelism, and also in a transversely converging relation to each other. The generated or evolution form of tooth-surfaces is thus restricted to one gear (the pinion) of the pair, while the other gear, or wheel, has non-evolved teeth of a shape and relative size 80 which are more readily producible with the 85 required high degree of precision, and which are both producible and repairable by the use of simple and ordinary appliances and methods, and without requiring the use of any "generating machines" for forming or 90 shaping the tooth-surfaces.

It will be remembered, that generally the rate of wear of the teeth on the two gears in any pair, is substantially in inverse proportion to the numbers of teeth thereon. 105 Thus in a pair of gears having respectively twenty and sixty teeth, the wear of the teeth on the twenty-tooth pinion evidently would normally be three times as great as on the sixty-tooth wheel. The more rapid 110

wear of the teeth of the smaller wheel, tends to continuously maintain and shape these teeth to the proper conjugate form for working correctly with the teeth of the larger wheel, provided these wheel teeth are of a precisionized character. Assuming that the gear and pinion ratios average three to one, then it is evident that three-fourths of the whole number of teeth, in this kind of gearing, can now be made without the use of "generating" machines, and without employing the "evolution" method, and still have the gears operate as truly and accurately as if the teeth of both gears were made by that method in gear-tooth generating machines.

In view of the intricate kinematical relations involved in the art of toothed-gearing,—and especially when the teeth are angularly-disposed, as in the present improvements,—I have herein employed the term "wheel" for designating the gear having the teeth thereof provided with the working-faces having a single-reproduction configuration, and have designated the mating gear as the "pinion", without regard, however, to their relative actual sizes but having in mind that usually the wheel is larger than the pinion, and that while either one may be used as the driver, the smaller said gear will preferably and usually be the pinion and be employed as the driving member of the pair of gears.

In the accompanying drawings forming a part of this specification, my present improvements are generally illustrated in the several figures by a delineation of a fragmentary portion only of a complete wheel or pinion, as the case may be, since in any case the complete periphery or toothed-zone of the wheel is only a duplication of the construction within one pitch-arc thereof; and similarly as to the pinion.

In the drawings, Figure 1 is a diagrammatic view illustrating (but in a general way only) certain relations of the wheel and pinion, and especially the relations of their respective tooth-surfaces with each other.

Fig. 2 is a fragmentary sectional view (drawn in alinement with Figs. 1 and 3, as indicated by the dotted line α α , which in Fig. 1 passes through the master-form axis at α) showing portions of a spur-wheel and pinion having teeth which are here shown in side view, and which correspond in construction with those indicated in end view in Fig. 1.

Fig. 3 is a similar fragmentary sectional view showing portions of a bevel wheel and pinion having teeth which are here shown in side view, and which correspond in construction with those indicated in end view in Fig. 1.

Fig. 2^a is a fragmentary view drawn be-

low and in alinement with Fig. 2, and showing in a portion of the spur-wheel B (Fig. 2), and in plan or face view, a pair of tooth-surfaces, as f^3 , f^5 , arranged with a tooth-space between them and also located with an obliquity indicated by the angle e^6 .

Fig. 3^a is a similar fragmentary plan or face view of a portion of the bevel wheel B, (Fig. 3), showing a pair of the tooth-surfaces, as f^3 , f^5 , arranged on the face or tooth-zone N, with the master-form axis α located in a plane of the axis-of-revolution, e , of the wheel.

Fig. 4 is a view similar to Fig. 3^a, but showing the pair of tooth-surfaces arranged on the tooth-zone or face, N', with an obliquity as indicated by the angle e^6 .

Figs. 5 and 6 are views in the nature of diagrams, and are arranged in a perspective manner for illustrating certain features as regards the relative locations of wheel and pinion axes and tooth-surface obliquity, in the case of "spur" gearing in Fig. 5 and of "bevel" gearing in Fig. 6.

Fig. 7 is a diagram drawn in a manner similar to a perspective view, for illustrating the geometrical relations of certain features of the wheel member of a pair of the gears, and for showing the master-form axis in three arrangements or locations coinciding, respectively, with three locations of a certain hypotenuse line which is here shown in the successive positions α , α^{12} and α^{13} .

Figs. 8, 8^a and 8^b, are fragmentary views (similar or corresponding to Figs. 1, 2 and 2^a, respectively,) drawn in projection with each other and illustrating pairs of tooth-surfaces as seen in end-view, (Fig. 8), in side-view, (Fig. 8^a), and in plan or face-view, (Fig. 8^b), respectively, when the master-form axis, α , is located in position α^{13} , Fig. 7, and the wheel B is a "skew-spur" gear.

Figs. 9, 9^a and 9^b are fragmentary views (similar or corresponding to Figs. 1, 3 and 3^a, respectively), drawn in projection with each other and illustrating pairs of tooth-surfaces as seen in end-view (Fig. 9), in side-view (Fig. 9^a), and in plan or face-view (Fig. 9^b), respectively, when the master-form axis α is located in position α , Fig. 7, and the wheel, B', is a "bevel" gear.

Figs. 10, 10^a and 10^b, are fragmentary views (similar or corresponding to Figs. 1, 3 and 4, respectively) drawn in projection with each other and illustrating pairs of tooth-surfaces as seen in end-view (Fig. 10), in side-view (Fig. 10^a), and in plan or face-view (Fig. 10^b), respectively, when the master-form axis, α , is located in an intermediate position, as α^{12} , Fig. 7, and the wheel B' is a "skew-bevel" gear.

Fig. 11 is a diagrammatic view showing a pair of wheel tooth-surfaces as seen in

view (as in Figs. 1, 8, 9 and 10) when the profile-lines,—as f , f' ,—are arranged to coincide with a master-form that is symmetrically located with reference to a meridian line, as m^2 , passing through the master-form axis x , and preferably located radially of the axis of revolution, (as x^3 , Figs. 1, 2 and 7) of the wheel.

Figs. 12 and 13 are views similar to Fig. 10 11 for illustrating certain features of the "master-form" and of the arrangement of the profile-lines of a pair of wheel tooth-surfaces.

Fig. 14 is a diagram for illustrating certain features hereinafter more fully explained, regarding the outward and the inward arrangements of the convergence of the tooth-surfaces.

Figs. 15, 16 and 17 are diagrammatic views illustrative of the preferred method of making the gears when the wheel B (in a conical form thereof) has the master-form planes inwardly-converging.

Figs. 18 and 19 are views similar to Figs. 25 15 and 17, respectively, for similarly illustrating the method when applied to the making of gears in which the said master-form planes are outwardly-converging.

Fig. 20 is a side view, chiefly diagrammatic, of the pinion, P, as seen from the left-hand in Fig. 19; these two views are drawn in alinement to facilitate the comparison thereof.

Fig. 21 is a face view of a portion of the pinion as seen from above in Fig. 20, with this difference however, that the tooth-zone is here shown as if the pitch-surface, (the geometric cone of revolution formed by the master-form axis, when this is revolved about the pinion-axis), were unrolled into a plane, for thereby bringing all the pinion-teeth to stand as if vertically disposed in a plan view, to facilitate description and comparison.

Fig. 22 is a view in all respects similar to Fig. 21, with the exception, that whereas in Fig. 21 the geometric master-form is applied to the tooth-spaces, (in correspondence with Fig. 19), this master-form is here shown applied in Fig. 22, to the pinion-teeth, thus producing the form of pinion-tooth having the longitudinally-parallel construction or configuration and with the intervening tooth-spaces of the longitudinally-tapering formation, in accordance with Fig. 17.

Fig. 21^a is an enlarged fragmentary view showing a pair of pinion teeth corresponding to those indicated in Fig. 21, as seen in 60 the direction of the arrow in Fig. 20.

Fig. 22^a is a view similar to Fig. 21^a, but showing pinion teeth and spaces arranged as in Fig. 22, and with these teeth having their wheel-engaging surfaces conforming 65 to the compound-reproduction configura-

tion, which is hereinafter more fully explained.

Figs. 23, 24 and 25 are views similar to Figs. 15, 18 and 16, respectively, for illustrating the counter-part tools J and T for 70 making pairs of tooth-surfaces in skew-spur wheels by the method of single-reproduction, and when the master-form-axis x is in the position x^{13} , Fig. 7.

Fig. 26 is an oblique view for more fully 75 and clearly exhibiting the features indicated in Figs. 23, 24 and 25.

Fig. 27 is a view similar to Fig. 17, for illustrating the manner of applying the master-form tool T (Fig. 23) for making 80 pairs of generated tooth-surfaces on the skew-spur pinion, by the method of compound-reproduction, and for mating with a skew-spur wheel such as indicated in Figs. 1, 2, 2^a, in Figs. 8, 8^a, 8^b, and in Figs. 23, 85 25, 26.

Fig. 27^a is a view drawn in alinement with Fig. 27, showing the skew-spur pinion, (as seen from the left-hand in Fig. 27), and Fig. 27^b is a view of the said pinion as 90 seen from above in Fig. 27^a.

Figs. 28 to 34^b inclusive, are a series of diagrams for illustrating,—more especially,—the geometrical relations, (at successive planes of revolution along the length 95 of a pair of spur-wheel tooth-surfaces) of the master-form axis and the trace-line thereof which constitutes an axial line within the mating pinion tooth, in a case where said master-form axis has a position 100 or arrangement relatively to the axis of revolution, (x^3 , Figs. 1 and 2) such as indicated by the hypotenuse-line x , in position x^{13} , Fig. 7.

Figs. 35 and 36 are diagrams illustrative 105 of certain features hereinafter more fully explained.

Similar characters designate like parts in all the figures.

In this system of oblique toothed gearing, the pinion has the working-surfaces of its teeth, (which are sometimes herein also designated as "tooth-faces", and as "tooth-surfaces"), shaped according to a compound-reproduction, which may be effected,—as hereinafter set forth,—by means of the counterpart tool having a movement parallel to the obliquely-located axis, as x (see Figs. 16, 17) of the master-form, as F, of the wheel, and also having concurrently 110 with and relatively to the pinion, a rolling movement in accordance with the geometric pitch-surfaces. Thus the wheel member of a pair of the gears is a master-wheel which is operable with a plurality of pinions of 115 different sizes, and located in various axial and angular relations to the wheel axis. Therefore, one such master-wheel may mesh with and drive at the same time several such pinions each having a different diameter. 120 125 130

Or, one such master-wheel may similarly mesh with several pinions of the same size but each having a different axial position relatively to the wheel-axis. Of these two arrangements, the former is briefly and diagrammatically indicated in Fig. 36, where the one master-wheel, B, coacts at the same time with the pinions P^5 , P^6 and P^7 , each of a different size. The second said arrangement is similarly indicated in Fig. 35 where the pinions P^8 , P^9 and P^{10} are of the same diameter, but have each a different axial position relatively to the axis x^3 of a coacting master-wheel, as B,—which may be the same master-wheel as designated by B in Figs. 2, 2^a, 8 and 10. Any convenient plurality of such mating pinions may be operated in mesh with one and the same master-wheel, provided, of course, that each of said pinions so employed shall be located free of the other pinions of any such assemblage or set. This peculiar and comparative universality which I thus obtain as regards the pluralities of pinions,—and as regards the varying arrangements thereof in which all of the pinions are correctly operable with one and the same mating wheel,—becomes greater in its range of practical application, in proportion to the increase of diameter of the master-wheel.

In a pair of intermeshing gears, and as between the body of a wheel-tooth and the body of a pinion-tooth, the proper rolling movement requires, in any given instance, some aggregate amount of transverse-curvature, or profile deviation, of the one tooth-surface relatively to the other, and in the former practice it was customary to apportion that total relative curvature one part to the wheel and the remaining part to the pinion and to make a different apportionment for each pair of gears having different relative diameters. In this system of gearing, and contrary to that former practice, no such separate apportionments are required, but the whole of such relative deviation may be applied to the pinion-tooth-surfaces. This feature combined with the longitudinal-parallelism of the pairs of wheel tooth-surfaces, and with these surfaces transversely converging, is a means for bringing the two said members of the pair of gears into such a relationship that in addition to having the improved operational features herein set forth, the wheel-teeth can be made on a series of wheels by the single-reproduction method and with the same master-form and the same counterpart tool, while only the pinions require the compound-reproduction method for their manufacture. This improvement in the method of manufacture, however, is not specifically claimed in this present application.

In a pair of mating gears for operating in only one direction, each of the coacting

teeth need have,—as is well known,—only one working-surface, but these working-surfaces, in the gearing herein described, are of the single reproduction arrangement and configuration on the wheel-teeth and have uniform profiles throughout their length, while the coacting tooth-surfaces on the pinion teeth are conjugate to said wheel-tooth working-surfaces and are of the compound-reproduction arrangement and configuration. Each wheel-tooth working-surface has uniform profiles throughout the length thereof and is of the single-reproduction configuration, but when each of said teeth has two such working surfaces, and has these arranged in such relation that a pair of them (either two surfaces on one tooth or two surfaces on each of two adjacent teeth), are formed in parallel, such pair of working-surfaces is said to conform to the single-reproduction arrangement and configuration; and conversely, the coacting pinion-tooth working-surfaces will then be formed in pairs which are said to conform to the compound-reproduction arrangement and configuration. When thus organized, each pinion-tooth is provided with a pair of working-surfaces which are individually conjugate to the respective working-surfaces of said wheel-tooth pairs, and which also, when taken as, or in pairs, conform to the compound-reproduction arrangement and configuration. In these arrangements, the wheel-tooth working-surfaces are, of course, "transversely-converging," either outwardly, as in Fig. 14^a, or inwardly, as in Fig. 14.

It will be remembered that the custom of making a tooth section symmetrical with a central line, as m^2 , Fig. 12, (this line being located in a plane radial to the axis of rotation), is for the purpose of making the pair of gears operate the same in either direction. But when the wheels are running in some one direction (as, for instance, in the direction of the arrow r^2 , Fig. 1) and the pinion is the driver, only the rearward faces, as f^3 , are the working-faces of the driven wheel-teeth, while the opposite faces, as f^6 , then operate as reaction faces for preventing an irregularity of movement because of any tendency to throw the wheels forwardly too rapidly, and thereby regulate the relative movements of the wheel and pinion with precision. Thus the actuation of the wheel B by the pinion P only involves the said one series of driven faces,—or tooth-surfaces,—of the wheel B (which I designate as "action-faces") and the coacting series of forwardly-acting or driving faces,—or tooth-surfaces,—of the pin P.

Usually the larger gear, as B, Figs. 2 and 5, of a pair of these oblique gears is properly regarded as being the "wheel." This wheel member is provided with obliquely-disposed teeth which have their working-

surfaces arranged in transversely-converging pairs in which each of said tooth-surfaces has a uniform profile throughout the length thereof. These tooth-surfaces are 5 also arranged in pairs which are longitudinally parallel the one to the other, so that in any such pair of tooth-surfaces their normal operation involves a peculiar progressively meshing-action as between the wheel 10 tooth-faces and the faces of a co-meshing pinion. This peculiar meshing action,—for the sake of brevity and for the want of a better term,—I have designated as a “skew-action.” In this gearing, therefore, there is 15 a certain skew-action of the tooth-faces which is normal to the operation of the gears, and which involves a relatively progressive meshing, longitudinally of the teeth during the approach into full-mesh,—so that 20 some variation in the skew angles does not, in effect, create a different kind of coaction, although varying the same in both a qualitative and a quantitative manner. Thus a skew-action involving a longitudinally-progressive meshing, as between the working-surfaces of the obliquely-disposed wheel-teeth and the coacting but differently shaped surfaces of the pinion teeth, is obtained with 25 pinions of different sizes and having respectively, different skew or angular locations of 30 the pinion-axis relatively to the wheel-axis.

In the style or outline of the master-form F as shown in Fig. 12, this conforming to Figs. 23 to 27, showing profile lines each 35 of a uniform contour throughout the length thereof, as elsewhere herein set forth, the reversely-disposed profile-lines f^3 and f^5 are drawn as conic-section lines, since these profile-lines are not only curved but are also 40 circular in character; and these circular-arc, conic-section profile-lines are not only converging in relative arrangement, but are shown so proportioned that they meet on a line, as nf^6 , that is tangential to said profile-lines, and that constitutes a meridian-line 45 for, or of, the master-form. In a similar manner, arcs of the other conic-section lines or curves may be arranged as the profile-lines of a master-form suitable for use in 50 shaping by the methods of single-reproduction and compound-reproduction, respectively, the working-surfaces of the teeth of the wheels and pinions, respectively, in pairs of gears made according to my present invention.

By the term “conic,” or conic-section as herein employed with reference to the preferable lines of curvature or uniform contour for the master-form profile-lines, I have considered the circle as being comprised in the 60 class of curves usually designated as “conic-sections,” and which are sometimes referred to by the simple term “conics.”

The aforesaid directly-coacting faces being arranged in converging pairs, and these

pairs, as f^3 , f^6 , Fig. 14, and f^3 and f^5 , Fig. 14^a, being alike except as to the direction of the convergence (here shown by arrows), each such pair of the converging faces constitutes a structural feature which I designate as the “master-form”. A further feature of this “master-form” is the longitudinal parallelism of the said two transversely-converging tooth-surfaces which are comprised therein, and the similar parallelism 70 of the surface-element lines of such tooth-surfaces relatively to a geometric “master-form-axis”, as x . In some of the views the master-form is shown applied to the wheel-tooth, which thus has parallel faces, while in other views the master-form is shown applied to the tooth-spaces, as F, the wheel-tooth surfaces,—as f^3 , f^5 ,—being shown offset in parallel from the master-form-axis x , as will more clearly appear from the detailed description of the several figures of 80 the drawing.

In a pair of these gears, when the wheel has the master-form with its center-line, as x , (see Figs. 3^a and 9^b), in the position x , 90 Fig. 7, where said center-line is shown located in a plane radial to the wheel axis, the two tooth-surfaces, as f^3 and f^5 (see Fig. 3^a), have a skew-angle, e^{13} , relation to said wheel-axis, one of them, as f^3 , has a rearward skew. 95 Similarly, the pinion P has its tooth-surfaces arranged with their bounding master-form surfaces, and hence their surface elements in general,—located on similar skew-angles, and these in relatively the same order of arrangement. When the action-face, as f^3 , of the wheel has a rearward skew, (see Fig. 3^a), the amount of which is indicated by the angle e^{13} , the coacting pinion tooth-surface 100 will have a corresponding amount of skew in the said direction. In this pinion construction, therefore, the master-form of or for the pinion tooth-surfaces has the two sides thereof in longitudinal parallelism, in 105 this respect corresponding with the wheel construction. When the wheel master-form has the inwardly-converging longitudinally parallel surfaces (and therefore has the parallel spaces, as F) the pinion master-form has,—relatively to the pinion pitch-surface,—the outwardly-converging arrangement of the said “master-form” bounding-surfaces or tooth faces. Therefore these two master-forms come into the same positions 110 and coincide when the two engaging tooth-sections also come to the exact full-mesh position, this being illustrated in Figs. 8, 8^a and 10, 10^a.

In each of the described arrangements of the convergence of the said wheel tooth-surfaces,—as indicated for instance in Figs. 8^a, 8^b and 10^a, 10^b, respectively,—these wheel-tooth surfaces, (in any series of the master-forms having the longitudinally parallel construction), are so arranged and related 120 125 130

- that,—as shown in Fig. 4,—in any group of three successive tooth-faces, two of these are arranged in parallelism with each other, and since in practice at least three successive wheel-tooth faces will be in mesh to the extent of having a full working engagement, therefore at all times in such a set of three successive faces there is a direct parallel (directly opposite) action and re-action, respectively, upon a pair of longitudinally-parallel faces which are one of them next succeeding to the other of them in the circumferential tooth-zone N of the wheel. This peculiar relationship and mode of co-action, is indicated in Figs. 3^a and 4 and other views, and particularly in said Fig. 3^a, where the two inwardly-converging successive faces 21 and 22 are in parallel, while the next successive face, 23, is at an angle, as ℓ^2 , thereto. Also in said Fig. 3^a, another set of three successive faces comprises the two outwardly-converging longitudinal non-parallel faces 22, 23, and the next succeeding parallelly-disposed face 24. In each of these two sets or groups, the directly opposite action and reaction is indicated by the parallelism of the two oppositely-acting faces, as 21, 22, in the one set, and 23, 24 in the other set.
- 30 The sheet of drawing comprising Figs. 28 to 34^b, inclusive, constitutes a single and comprehensive diagram, which is composed of several series of small diagrams that are separately designated, and are drawn in alignment, or projection, in a conventional manner, to facilitate comparison. In the plan-view diagram Fig. 29, the line α is the same master-form axis, α , shown in Fig. 26, and successive points along this line (within the length of a tooth-space) are shown at α , in Figs. 30, 31, 32, 33 and 34, respectively; also, the line α in Fig. 28 is the line α of Fig. 29, as it would appear when somewhat produced and then seen from below in Fig. 29. In these views, the profiles and the point α , correspond in their relations, with the same elements as illustrated in other figures, including Figs. 11, 14 and 15. For convenience, only five of the small diagrams are shown in one series; Fig. 32 shows the master-form and profiles-position as in a mid-plane of rotation, in the length of gear tooth-space, when the gear is rotated to bring the line α to coincide with the geometric instant axis; Figs. 30 and 34, represent those relations in planes of rotation at the ends of the tooth-space, while Figs. 31, 33, represent the said relations at intermediate planes of rotation along the axis, α^3 , of the wheel.
- 60 The line α , Figs. 28, 29, being located in a diagonal position and also a straight line, (corresponding to line α^1 , Figs. 7, 2^a), only one point therein comes to the instant axis in the geometric rolling surfaces of the wheel and pinion, and this deviation is shown by

the divergent positions of the lines α and V in Figs. 28, 29, also in the views 30^a—34^a, and 30^b—34^b.

As regards the relations of the coacting pairs of wheel-tooth working-surfaces and the corresponding pinion-tooth working surfaces, these progressive relations are further exhibited in Figs. 28 to 34^b, inclusive, and they may be said to be derived from and to follow the master-form-axis α (see Fig. 29) as regards the wheel-tooth surfaces and the corresponding trace-line V, as to the pinion-tooth surfaces. These relations, therefore, involve the single reproduction and the configuration resulting therefrom, as compared with the compound-reproduction and the peculiar curved surfaces resulting therefrom. But as regards the relation of the profiles of the said pairs of surfaces to a radius of the wheel at any particular point in the length of the tooth surface, (that is with relation to any plane of rotation), these profiles are, of course, determined by the single reproduction method as regards the wheel-tooth working-surfaces (as in Figs. 30 to 34), while the coacting and conjugate pinion-tooth profiles have a curvature which results from and corresponds with the epicycloidal relations at successive points along the instant-axis, as m , Fig. 7, or x , Fig. 2^a. Thus, it may be said that the general proportion and formation of the said two pairs of surfaces of the wheel and pinion, respectively, are the result of the single reproduction and the compound reproduction (as elsewhere herein more fully described) with relation to a master form axis which, as regards the wheel, lies obliquely to and outside of the pitch surface; and also with relation to a pinion-tooth axis which lies within the pitch surface of the pinion. Successive positions of the trace-line V are shown in side view in Figs. 30^a to 34^a, while the same positions are shown in end view, in Figs. 30^b to 34^b, respectively; both of these series of views are drawn in projection with the plan-view diagram, Fig. 29, as shown by the usual dash-lines. In all these views the normal, or more usual, deviation of the trace-line V relatively to, or away from the axial line α , is somewhat exaggerated so that the diagrams may be more easily compared. Fig. 28 corresponds in position with Fig. 32^b.

Referring to the diagram Fig. 7, if a line, as 2^a, which is a normal to the axis α^3 at the point c , be rotated about said axis, the outer end of said line 2^a describes the meridian circle m^3 , located in a plane of rotation. At some other point, as c' , on said axis α^3 , describe a similar circle as m^4 also in a plane of rotation; the two circles then lie in parallel planes and these planes are at right-angles to the axial line α^3 which represents the axis of rotation of any gear or wheel that shall be drawn out or designed in ac- 130

cordance with the diagram thus arranged or proportioned. In practice, as will be evident, the diagram, Fig. 7, may be made of such proportions as are suitable for meeting the requirements in any given pair of gears to be made in accordance with my present improvements. It will be seen that the circle m^5 is an orbital path in which the point z may be said to revolve around the point y of the circle m^4 . Said orbital circle m^5 is shown divided by the lines 3^a 3^b into arcs of which the quadrant c' to z is the lower right-hand quadrant, extending in the circle m^5 from the line x , at the point c' , to the line x^{13} , at the point z ,—these lines x and x^{13} being different positions of a hypotenuse line.

The said hypotenuse line, as x^{13} , at the vertex xx of the triangle xx, y, z , Fig. 7, intersects or contacts with the instant axis m , and this is in a plane of rotation which, for convenience, I designate as the meridian plane, and in which lies the circle m^3 ; this plane is also the "profile" meridian. When the described locating-triangle xx, y, z , Fig. 7, has the plane thereof, (which is indicated by the line $y z$), located in a tangential relation to the meridian-circle m^3 ,—and also tangential to the geometric surface-of-revolution generated by the master-form-axis revolving about the wheel-axis x^3 , and the tooth-zone of the wheel, as N' , Fig. 2^a, being located contiguous to said meridian-circle m^3 , the gear-wheel (see Fig. 26) is then of the particular kind which I designate as "skew-spur" gearing.

In a pair of these gears, when the wheel has the master-form with its center-line, as x , Fig. 7 in the position z , (which is also in a plane radial to the wheel axis) the two tooth-surfaces, as f^3 and f^5 (see Fig. 3^a) have a skew-angle relation to said wheel-axis, one of them, as f^5 , having a forward skew while the other said face, as f^3 , has relatively a rearward skew. Similarly, the pinion P has its tooth-surfaces arranged with their bounding master-form surfaces,—and hence their surface elements in general,—located on similar skew-angles, and these in relatively the same order of arrangement. When the action-face, as f^5 , of the wheel has a rearward skew, the amount of which is indicated by the angle e^{13} , the coacting pinion tooth-surface will have a corresponding amount of skew in the said direction. In this pinion construction, therefore, the master-form of the pinion tooth-surfaces has the two sides thereof in longitudinal parallelism, in this respect corresponding with the wheel construction. But when the wheel master-form has the inwardly-converging longitudinally parallel surfaces, (and therefore has the parallel spaces, as F (Fig. 1) the pinion master-form has,—relatively to the pinion pitch-

surface,—the outwardly-converging arrangement of the said "master-form" bounding-surfaces or tooth-faces. Therefore these two master-forms come into the same positions and coincide when the two engaging tooth-sections also come to the exact full-mesh position, this being illustrated at x , Fig. 1. 70

From the foregoing description as herein illustrated, it will now be evident how the master-form-axis is not only a line located 75 in a plane, but also is a line having an angular position relatively to the wheel-axis, to the plane of rotation and to any straight-line that is a normal to (vertical to) such plane of rotation; and how, in the pinion, 80 the corresponding tooth-surface axial-lines (as V , Figs. 28, 29),—of the respective tooth-surface pairs,—are rotational trace-lines of said wheel master-form-axes, x , as more fully explained in connection with said composite diagram, Figs. 28 to 34^b.

In practice, any desired number of exchangeable pinions of different sizes respectively, may have their working-surfaces shaped by the method of compound-reproduction, or "evolution," from and by the counter-part of the same master-form F , by generating the pinion teeth from a rolling movement on the geometric pitch-surfaces. In this operation pitch-surfaces resulting 95 from the rolling movement will, of course, meet on an axial line, as x , Figs. 17 and 27. In any such case, however, the same counter-part tool, as T , having a profile outline coinciding with said master-form (or a suitable correspondingly-shaped milling-cutter,—not shown,—in lieu thereof,) will properly generate the corresponding pinion-tooth curved-surface of the conjugate form for working correctly upon the tooth-surfaces of 100 such master-wheel. Thus a single master-wheel may constitute a master or form for generating the teeth on any plurality of pinions of different sizes, respectively, and each specially shaped for rolling correctly 110 in mesh with that one master wheel; but these different pinions, being each thus specially shaped, are not thereby formed for working in mesh with each other, nor with a master-wheel of a different size or proportion. In all such instances, however, the pinion tooth-surface may be properly described as having a developed curvature generated "according to" the tooth-surfaces of 120 the mating master-wheel of the pair. These pinion tooth-surfaces are said to be "generated" because in practice they will be, usually and preferably, produced in and by some suitable gear-tooth-generating machine, the tooth-surfaces being developed 125 from and by a tool whose cutting lines are made "according to" the "form" of the master-wheel pairs of tooth-surfaces, so that the resultant or conjugate "tooth-face transverse curvature" will be of the same "developed" 130

formation as if the tooth-surfaces of the pinion were actually molded into shape by the rolling of the pinion in mesh with its own master-wheel.

- 5 As an aid to a full and clear description of the gearing, I will now briefly explain one method of making the master-form surfaces of the wheel, (first referring to conical wheels having obliquely-disposed tooth-surfaces,) and the use of the counter-part tools for making of the conjugationally-curved pinion-tooth surfaces by the duplicate of the master-form of the wheel with which such pinion is to mesh.
- 10 In Fig. 15 the ellipse 8 is the outer circle of the wheel B, as seen in the direction shown in Fig. 10, the line of sight being parallel to the axis α of the centrally located master-form at F; this view also shows the working-surfaces of said master-form arranged inwardly-converging. In Fig. 16 a section is shown of the tooth-rim of the wheel B, as seen from the right-hand in Fig. 15, the tooth-surface f^3 being shown 20 fully formed, while the master-form-axis α indicates, also, the line of movement of the tool J, the profile-outline of which (Fig. 15) should correspond with some selected master-form F, (Figs. 12 or 13) for the wheel 25 B. The wheel-blank being properly held in a well-known manner in a suitable indexing-shaping machine (not shown), and the tool J being reciprocated while carried in the usual tooth-holder of such well-known shaping machine, the tool may then be fed gradually downward to its said position in Figs. 15 and 16, thereby "reproducing" the form of the tool in a reversed arrangement in the wheel rim and with only a "single" direction 30 or kind of movement as between the wheel and the tool and thus completing one pair of parallel tooth-surfaces by the "single-reproduction" method. This operation being repeated around the wheel at each pitch-arc 35 interval, all the tooth-faces will be similarly completed.

In said Fig. 15, for the purpose of comparing a pair of tools, a counterpart-tool, T, is indicated by dotted lines in a position in 40 which it exactly matches the aforesaid tool J, and is an exact counterpart of the tooth-form F of the wheel. Such a counterpart tool is shown at T, Fig. 17, as employed for making the pinion-tooth g of a conjugate-curve for correctly operating with the aforesaid tooth-form faces f^3 and f^5 of the wheel. For this purpose, the tool T may be given the well-known "planer movement" in the line of the tooth-form axis α (coinciding 45 with the line of sight in Figs. 1 and 10) and at the same time will swing in a circle, as 8 (herein seen as an ellipse) coinciding with the geometric pitch-surface of the wheel; that is, the tool T has a "compound" motion, comprising a reciprocatory or working

movement in the line of the "instant-axis" of the wheel, while this line of movement also revolves about the axis of the wheel. It will be seen, however, when the wheel-tooth profile is a straight-line, such a coincidence of the line of tool movement with the instant axis is not required. During this compound or generating operation, the pinion blank P also revolves, (as indicated by arrows in Fig. 17) until the tool T has 75 swung from the initial position T' to the final position T'' , thereby completing both of the faces of the pinion-tooth g by a single operation of the machine, and by a method of "compound-reproduction" whereby the 80 complete "master-form" with its surfaces of uniform profile and parallel construction is reproduced in a conjugational manner in the curved faces of the similarly parallel pinion teeth such as shown obliquely-located in the 85 pinion body P in Fig. 22^a.

Figs. 18 and 19 correspond to said Figs. 15 and 17, respectively with the exception that the tools J and T have changed places, the tool T being shown in Fig. 18 as used for 90 making the wheel-tooth, and with the master-form faces outwardly-converging, but with the single-reproduction, as before. In the companion view, Fig. 19, the counterpart tool J is shown as used for "generating" the corresponding and oppositely-disposed curved faces of the pinion-teeth, with and between which the said wheel-tooth g is to directly co-act. Thus in each arrangement of the master-form, the two counterpart tools by one operation of each of the tools produce four faces arranged in two pairs for direct co-action, and arranged on the lines of parallel master-forms which are identical for both the wheel and the pinion. 95

In Fig. 20, the pinion P is shown in correspondence with the same member in Fig. 19, except as to the inclined position of the pinion axis, α^6 , which is here shown inclined for bringing the instant axis, α , into alignment with the point x, in Fig. 19,—this point being, in Figs. 17 and 19, the projection of the instant-axis. In Figs. 21 to 22^a, the dotted lines i , i' , indicate the surface-elements which come to parallelism when the mating wheel and pinion teeth come to a symmetrical position, one instance of which is illustrated in Fig. 9, for the form of tooth shown in Fig. 22^a. This is particularly indicated in Fig. 21^a where the parallel lines i , i' , are the bearing lines of which the lines i , i' , (Fig. 21) are projections. The curved character of the working surfaces of the tooth g, Fig. 21, is indicated by the curvature of the lines already described, and is further indicated in Figs. 21, 21^a, by the slightly curved bottom and top lines j and j' , respectively, but these curvatures are slightly exaggerated for making these diagrammatic representations appear more 110 115 120 125 130

clearly on the drawing. For the tapering form of pinion-tooth, as in Figs. 21, 21^a, a corresponding symmetrical position is indicated in Fig. 19, where the wheel-tooth position is indicated by the tool J, located between the two pinion-teeth g, g.

In the side view Fig. 20, of course the bottom and top lines j, j', appear as straight lines. This Fig. 20, although drawn in projection with Fig. 19, would also be correct if similarly drawn in projection with Fig. 17, since, on the scale here illustrated, such a side view of each form of pinion-tooth will be nearly the same. In Figs. 21 and 21^a the pinion-teeth g are shown having the longitudinally-parallel configuration, in accordance with Figs. 10 to 10^b; and when "F" is assumed to be a wheel tooth-space and "h" is a tooth; but in Figs. 21 and 21^a, the pinion-teeth, g, have the described tapering formation, and also the obliquely-disposed location.

The "form" or configuration of a tooth-surface may be said to include the features of outline, or profile, and the relative position thereof. The character of the profile depends, of course, on the kind of reproduction, whether single, (as in the case of the wheel),—or compound, as in the case of the pinion; the position depending on the direction of the transverse convergence, whether inwardly or outwardly. As thus applied to the wheel, each profile or side-line, as f³ or f⁵ (Figs. 12 to 14^a) of the form F, gives,—always by the same direct reproduction,—the shape or profile, and also the position or angular relation, to one tooth-surface in each said arrangement of the wheel construction. In the primary arrangement, the said master-form,—as represented in a tool (as T, Figs. 17, 27), that is coincident therewith,—and by the use of the single-reproduction method, produces a pair of tooth-surfaces bounding the body of one and the same tooth, (Fig. 14^a), and therefore gives to this tooth an actual sectional shape and size which is the exact counterpart of said geometric master-form. In the secondary arrangement, the same results as to outline and relative position are produced (as by the tooth J, Fig. 19), on the two adjacent tooth-surfaces of two adjacent tooth-bodies, respectively, but with the sectional shape and size applied to the tooth-spaces.

In practice, it is desirable that the angular variations of the gear-axes shall only be adopted within moderate limits, but these limits, however, may vary somewhat from the specific proportions herein illustrated. The limits within which the relative location of the pinion axes may be varied as herein described, (as in Fig. 35, for instance) can readily be ascertained in practice by trial or by the aid of suitable graphic methods, having in view the extent to which in any

given instance the relative obliquity which may be desirable as between the pinion tooth-faces and the pinion-axis; in most cases an angle of obliquity of about 10 degrees is deemed to be within practicable working limits. The range of variation which in practice it may be feasible to adopt, as to axial obliquity, I have herein designated as the "coöperative relation" of the pinion axis relatively to the wheel-axis. In this connection it will, of course, be understood that the specific character or conjugate shape of the working surfaces of the pinion teeth will vary, in pairs of gears otherwise the same but having some particular axial obliquity in order to make such pinion surfaces properly conform to the required compound reproduction arrangement and configuration.

Since each wheel-tooth working-surface has uniform profiles throughout the length thereof and is of the single-reproduction configuration, when each said tooth has two such working surfaces, and these are arranged in such relation that a pair of them (either two surfaces on one tooth or two surfaces on each of two adjacent teeth), are formed in parallel, then such pair of working-surfaces is said to conform as pairs to the single-reproduction arrangement and configuration; and, conversely, the coacting pinion-tooth working-surfaces will then be formed in pairs which are said to conform as pairs to the compound-reproduction arrangement and configuration. When thus organized, each pinion-tooth is provided with a pair of working-surfaces which are individually conjugate to the respective working-surfaces of said wheel-tooth pairs and which also, when taken as or in pairs, conform as pairs to the compound-reproduction arrangement and configuration. The obliquely-located wheel-pair of said tooth-surfaces being of an untwisted form or construction, it follows that the mating pair of pinion tooth-surfaces will be not only obliquely-located but also will have a twist throughout the length thereof; this is especially illustrated in the sheet of diagrams, Figs. 28 to 34^b, in which the described twist is indicated in Fig. 29 by the divergent trace-line V relatively to the wheel master-form axis x.

The two described arrangements of the transverse convergence of the wheel-tooth working-surfaces in the longitudinally parallel pairs thereof, and the coöperation of the pinion therewith, are more fully illustrated and explained in my prior Patent No. 1,112,509, and therefore I have only briefly described this feature in the present application. Those two constructions as regards the transverse convergence are regarded as broadly included under one definition and hence are herein so described.

and claimed; but the inwardly-converging construction is regarded as having some important advantages, and especially since this form of the wheel has,—as compared with the other,—a reversed angular, or circumferential, "advance" of the tooth-face surface-elements of the "driving" (or "action") working-surfaces of the wheel-teeth, and has the peculiar "skew-action" and other special qualities and features of operation as elsewhere herein more fully set forth.

In the organization in the mating wheel and pinion, of the respective working-surfaces into the angularly-disposed coacting surface-pairs,—and in whichever direction the transverse convergence may be arranged,—it will be observed that each of the pinion-tooth working-surfaces is conjugate to one series only of the wheel-tooth working-surfaces, that is to those facing in the reverse direction; and therefore, it will be evident that the working-surfaces comprised in the two series of wheel-tooth working-surfaces, respectively, may be of different profiles, and may have different pressure angles. But in any such instance the two pinion working-surfaces which conform as a pair to the compound-reproduction configuration and arrangement, will be individually conjugate to the two wheel working-surfaces, respectively, which conform as a pair to the single-reproduction configuration and arrangement.

By reason of the sameness of organization as set forth of the master-forms of both wheel and pinion, and the reversal of the relative direction of the convergence (in the wheel and pinion, respectively, of a directly-coacting pair of these master-forms, (see Figs. 15, 18 and 23, 24) when the counterpart tool T (Figs. 17, 27) is employed for generating the pinion curved-surface tooth-faces, by the described compound-reproduction, it follows that this operation being begun at any one point may then continue without change until the entire length of the tooth is completely shaped, and with the result of forming the opposite tooth-surfaces of a transversely curved shape or profile which has a constantly changing profile-curvature throughout the length of the pinion tooth, and thereby producing on the pinion, a tooth characterized by the feature of having the opposite working-surface primary elements in parallelism. In the pinion P, Figs. 21^a, 22^a, the skewed teeth, *g*, are indicated as being of that form, said "primary elements" being indicated by the lines *i* and *i'*. In connection with the advantage of being able, (within a considerable range of proportions and sizes), to make by the use of the same counterpart tool, and by single-reproduction only, the teeth of all the wheels having a given pitch,—this system, as will

now be evident, has the further advantage of making the tooth-spaces of all sizes and varieties of pinions for such wheels by the use of only one form of tool, and this of only one size, operating by the method of compound-reproduction, or generation, now sometimes designated as "evolution". A direct result of those features is that a single pair of the counterpart tools suffice for making all the pairs of the gears (regardless of varying diameters and different obliquity angles), of a given pitch and size of tooth, thus reducing the cost of tools and of tool gages, and the cost of their maintenance, to the very lowest practicable basis.

An immediate and important practical result of this system of parallel-construction combined with angular-location as applied to both the pinion-teeth and wheel tooth-space from identical tooth-form profiles (in addition to the great advantage and economy,—as already explained, of eliminating the compound-reproduction otherwise required for making the wheel teeth,) is the complete elimination of the difficult setting and gaging operations which are necessary, as regards both wheel and pinion, in the manufacture of gears having teeth of a cross-section which varies in form or size, or both, along the length of the tooth. Also in this parallel-construction, the pinion tooth may be completely shaped and sized without the danger of a variation in widths of successive teeth being caused by any inaccuracy in the indexing of the wheel blanks, when the teeth are made by cutting operations; thus I avoid one of the causes of imperfection appertaining to the manufacture of skew-toothed, or oblique, gearing in gear-tooth-generating machines.

In the operation of the machine, in making the wheel, the reciprocating tool at all points in the tool-section,—including (of course) all points in the profile-lines,—moves in lines parallel to the line *wm6*, (in the symmetrical position of a pinion tooth), lies in (or in touch with) the geometric pitch-surface, and from which in the rolling movement of the gears, the similar line of the pinion describes an epicycloid at the point or points thereof which in said movement lie in both pitch-surfaces while at said symmetrical position. This is indicated in Fig. 17 by the paths 20, 20', of the master-form axis of the pinion, this axis being, so to speak, merged at *x* with the corresponding wheel master-form axis, since in the symmetrical position shown in Fig. 17, (also in Figs. 1, 8, 9, 10, 19, 23, 24 and 27), those two master-form axes coincide, that is, occupy the same positions.

From the diagram Fig. 35,—especially when compared with Fig. 7 and other views as herein described,—it will be evident that

when the wheel-axis and the pinion axis are not located in parallel planes, the obliquity or angular position of the working-surfaces of the teeth of the pinion will be correspondingly varied relative to the respective axes of revolution of the wheel and pinion, while the obliquity or angular position of the working-surfaces of the teeth of the wheel itself may be the same relatively to the wheel-axis, with a considerable variation in said pinion axial positions.

This invention, as will now be evident, furnishes a means and system whereby angularly-disposed or oblique-tooth gears operating correctly as skew-gears, are readily and cheaply producible without resorting to the usual but difficult forms involving the hyperbola-of-revolution. Furthermore, the described skew-gears may now be made with the same economy and facility as non-oblique gears, and may be produced in and by the same machines and appliances. These improvements, therefore, practically eliminate from the gear-making art, one of its most difficult and unsatisfactory branches, and thus make available for a wide range of applications, the valuable features of the oblique-tooth gearing for use in many situations where, hitherto, the difficulty of manufacture and consequent high-cost have been prohibitive.

In my Patent No. 1,112,509, I have illustrated and described certain features of my present improvements as applied to toothed-gears of the "bevel" and "skew-bevel" kinds, and which have their teeth located at an angle to the axis of revolution and have the wheel-tooth working-surfaces made with a single-reproduction configuration that is distinguished by a master-form of straight-line profiles and tooth-surfaces coinciding with geometric-planes; these particular features, therefore, are not claimed herein, since the subject-matter of this application is not restricted to a master-form of straight-line profiles nor to tooth-surfaces in the form of true planes. This application, therefore, includes under one definition, not only the bevel and skew-bevel forms of a certain kind of gearing and as to certain features thereof, but also includes, under the same definition, a corresponding form of skew-tooth spur-gearing,—either with or without an axial skew,—in which the wheel-teeth have working-surfaces conforming to the single-reproduction configuration, and in which the mating pinion has coacting working-surfaces conjugate to said wheel-tooth surfaces and conforming to the compound-reproduction configuration.

In a copending application, Serial No. 325,216, I have described and claimed subject-matter which is disclosed in part in this present application, but which is not specifically claimed therein.

Having thus described my invention, I claim:

1. The herein described improvement in toothed-gearing, it consisting in a pair of gears comprising a master-wheel provided with teeth each having a working-surface with uniform profiles throughout the length thereof and each surface having surface-elements in alinement with a geometric master-form-axis which coincides with the hypotenuse of a plane-triangle another side of which, at a plurality of points in the length thereof, coincides with a line that is parallel to the wheel-axis, the vertex of said triangle being in the instant-axis of the gears, and said wheel-tooth working-surfaces conforming to the single-reproduction configuration, in combination with a mating pinion having its axis in co-operative relation to the wheel-axis, and having wheel-engaging teeth each provided with a working-surface conjugate to said wheel-tooth working-surfaces and conforming to the compound-reproduction configuration.

2. The herein described improvement in toothed-gearing, it consisting in a pair of gears comprising a master-wheel provided with teeth each having a working-surface with profiles of uniform curvature throughout the length of the profile and each surface having straight-line surface-elements in parallel with a geometric master-form-axis which coincides with the straight-line hypotenuse of a plane-triangle another side of which (at a plurality of points in the length thereof) coincides with a line that is parallel to the wheel-axis, the vertex of said triangle being in the instant-axis of the gears, and said wheel-tooth working-surfaces conforming to the single-reproduction configuration, in combination with a mating pinion having its axis in co-operative relation to the wheel-axis, and having wheel-engaging teeth each provided with a working-surface conjugate to said wheel-tooth working-surfaces and conforming to the compound-reproduction configuration.

3. The herein described improvement in toothed-gearing, it consisting in a pair of gears comprising a master-wheel provided with teeth each having a working-surface with profiles of uniform curvature throughout the length of the profile and each surface having surface-elements in alinement with a geometric master-form-axis which coincides with the hypotenuse of a plane-triangle another side of which at a plurality of points in the length thereof, coincides with a line that is parallel to the wheel-axis, the vertex of said triangle being in the instant-axis of the gears and the plane of said triangle being oblique to and intersecting a plane through the wheel-axis and said vertex, and said wheel-tooth working-surfaces conforming to the single-reproduction configuration.

duction configuration, in combination with a mating pinion having its axis in coöperative relation to the wheel-axis, and having wheel-engaging teeth each provided with a 5 working-surface conjugate to said wheel-tooth working-surfaces and conforming to the compound-reproduction configuration.

4. The herein described improvement in toothed-gearing, it consisting in a pair of 10 gears comprising a master-wheel provided with teeth each having a pair of transversely converging working-surfaces of which each surface has straight-line surface-elements in parallel with a geometric master-form axis 15 which coincides with the straight-line hypotenuse of a plane-triangle another side of which is parallel to the wheel-axis and the vertex of which is in the instant-axis of the gears, said wheel-tooth pairs of working- 20 surfaces conforming to the single-reproduction arrangement and configuration, in combination with a mating pinion having its axis in coöperative relation to the wheel-axis, and having wheel-engaging teeth provided 25 with working-surfaces which are conjugate to said wheel-tooth working-surfaces and conform to the compound-reproduction arrangement and configuration.

5. The herein described improvement in toothed-gearing, it consisting in a pair of 30 gears comprising a master-wheel provided with teeth each having a pair of transversely and inwardly converging working-surfaces of which each surface has straight-line surface-elements in parallel with a geometric master-form axis which coincides with the straight-line hypotenuse of a plane-triangle another side of which is parallel to the wheel-axis and the vertex of which is in the 35 instant-axis of the gears, said wheel-tooth pairs of working-surfaces conforming to the single-reproduction arrangement and configuration, in combination with a mating pinion having its axis in coöperative relation to the wheel-axis, and having wheel-engaging teeth provided with working-surfaces which are conjugate to said wheel-tooth working-surfaces and conform to the compound-reproduction arrangement and 40 configuration.

6. The herein described improvement in toothed-gearing, it consisting in a pair of 45 gears comprising a master-wheel provided with teeth each having a pair of transversely converging working-surfaces with uniform profiles throughout their length and each surface having surface-elements in alinement with a geometric master-form-axis which coincides with the hypotenuse of a plane-triangle another 55 side of which at a plurality of points in the length thereof, coincides with a line which is parallel to the wheel-axis, and the vertex of which is in the instant-axis of the gears, the plane of said triangle being oblique to and intersecting a plane through the wheel-axis and said vertex, and said wheel-tooth pairs of working-surfaces conforming to the single-reproduction arrangement and configuration, in combination with a mating 60 pinion having its axis in coöperative relation to the wheel-axis, and having wheel-engaging teeth each provided with a pair of working-surfaces which are individually conjugate to the respective working-surfaces of said wheel-tooth surface-pairs, and which in pairs conform to the compound-reproduction arrangement and configuration.

7. The herein described improvement in toothed-gearing, it consisting in a pair of 65 gears comprising a master-wheel provided with teeth each having a pair of transversely converging working-surfaces with uniform profiles throughout their length and each surface having straight-line surface-elements in parallel with a geometric master-form axis which coincides with the straight-line hypotenuse of a plane-triangle another side of which is parallel to the wheel-axis and the vertex of which is in the instant-axis of the gears, the plane of said triangle being oblique to and intersecting a plane through the wheel-axis and said vertex, and said wheel-tooth pairs of working-surfaces conforming to the single-reproduction arrangement and configuration, in combination with a mating pinion having its axis in coöperative relation to the wheel-axis, and having wheel-engaging teeth each provided with a pair of working-surfaces which are individually conjugate to the respective working-surfaces of said wheel-tooth surface-pairs, and which in pairs conform to the compound-reproduction arrangement and configuration.

8. The herein described improvement in toothed-gearing, it consisting in a pair of 70 gears comprising a master-wheel provided with teeth each having a pair of transversely converging working-surfaces with uniform profiles throughout their length and each surface having straight-line surface-elements in parallel with a geometric master-form axis which coincides with the straight-line hypotenuse of a plane-triangle another side of which is parallel to the wheel-axis and the vertex of which is in the instant-axis of the gears, the plane of said triangle being oblique to and intersecting a plane through the wheel-axis and said vertex, and said wheel-tooth pairs of working-surfaces conforming to the single-reproduction arrangement and configuration, in combination with a mating pinion having its axis in coöperative relation to the wheel-axis, and having wheel-engaging teeth each provided with a pair of working-surfaces which are individually conjugate to the respective working-surfaces of said wheel-tooth surface-pairs, and which in pairs conform to the compound-reproduction arrangement and configuration.

9. The herein described improvement in toothed-gearing, it consisting in a pair of 75 gears comprising a master-wheel provided with teeth each having a pair of transversely converging working-surfaces with uniform profiles throughout their length and each surface having surface-elements in alinement with a geometric master-form axis which coincides with the hypotenuse of a plane-triangle another 80 side of which at a plurality of points in the length thereof, coincides with a line which is parallel to the wheel-axis, and the vertex of which is in the instant-axis of the gears, the plane of said triangle being oblique to and intersecting a plane through the wheel-axis and said vertex, and said wheel-tooth pairs of working-surfaces conforming to the single-reproduction arrangement and configuration, in combination with a mating pinion having its axis in coöperative relation to the wheel-axis, and having wheel-engaging teeth each provided with a pair of working-surfaces which are individually conjugate to the respective working-surfaces of said wheel-tooth surface-pairs, and which in pairs conform to the compound-reproduction arrangement and configuration.

faces of said wheel-tooth surface-pairs, and which in pairs conform to the compound-reproduction arrangement and configuration.

- 5 9. The herein described improvement in toothed-gearing, it consisting in a pair of gears comprising a master-wheel provided with teeth each having a pair of transversely and inwardly converging working-surfaces with uniform profiles throughout their length and each surface having straight-line surface-elements in parallel with a geometric master-form axis which coincides with the straight-line hypotenuse of 10 a plane-triangle another side of which is parallel to the wheel-axis and the vertex of which is in the instant-axis of the gears, the plane of said triangle being oblique to and intersecting a plane through the wheel-axis 15 and said vertex, and said wheel-tooth pairs of working-surfaces conforming to the single-reproduction arrangement and configuration, in combination with a mating pinion having its axis in coöperative relation to the wheel-axis, and having wheel-engaging teeth each provided with a pair of working-surfaces which are individually conjugate to the respective working-surfaces of 20 said wheel-tooth surface-pairs, and which 25 in pairs conform to the compound-reproduction arrangement and configuration.
- 10 10. The herein described improvement in toothed-gearing, it consisting in a pair of gears comprising a master-wheel provided 30 with teeth each having a pair of transversely converging working-surfaces with profiles of a conic-section contour and uniform throughout the length of the tooth surface, and each surface having surface-elements 35 in alinement with a geometric master-form-axis which coincides with the hypotenuse of a plane-triangle another side of which at a plurality of points in the length thereof, coincides with a line that is 40 parallel to the wheel-axis, the vertex of the triangle being in the instant-axis of the gears and the plane of said triangle being oblique to and intersecting a plane through the wheel-axis 45 and said vertex, and said wheel-tooth pairs of working-surfaces conforming to the single-reproduction arrangement and configuration, in combination with a mating pinion having its axis in coöperative relation 50 to the wheel-axis, and having wheel-engaging teeth provided with working-surfaces which are conjugate to said wheel-tooth working-surfaces and conform to the compound-reproduction arrangement and configuration.
- 55 11. The herein described improvement in toothed-gearing, it consisting in a pair of gears comprising a master-wheel provided with teeth each having a pair of transversely and inwardly converging working-surfaces with curved profiles of conic-section 60 and each surface having straight-line surface-elements in parallel with a geometric master-form-axis which coincides with the straight-line hypotenuse of a plane-triangle another side of which coincides with a line that is parallel to the wheel-axis, the vertex 65 of the triangle being in the instant-axis of the gears and the plane of said triangle being oblique to and intersecting a plane through the wheel-axis and said vertex, and said wheel-tooth pairs of working-surfaces conforming to the single-reproduction arrangement and configuration, in combination with a mating pinion having its axis in coöperative relation to the wheel-axis, and having wheel-engaging teeth provided with working-surfaces which are conjugate to said wheel-tooth working-surfaces and conform to the compound-reproduction arrangement and configuration.
- 70 12. The herein described improvement in toothed-gearing, it consisting in a pair of gears comprising a master-wheel provided with teeth each having a pair of transversely converging working-surfaces with profiles of a conic-section contour consisting of a circular-arc and uniform throughout the length of the tooth-surface, and each surface having surface-elements in alinement with a geometric master-form-axis which coincides with the hypotenuse of a plane-triangle another side of which at a plurality of points in the length thereof, coincides with a line that is parallel to the wheel-axis, the vertex of the triangle being in the instant-axis of the gears and the plane of said triangle being oblique to and intersecting a plane through the wheel-axis 75 and said vertex, and said wheel-tooth pairs of working-surfaces conforming to the single-reproduction arrangement and configuration, in combination with a mating pinion having its axis in coöperative relation to the wheel-axis, and having wheel-engaging teeth provided with working-surfaces which are conjugate to said wheel-tooth working-surfaces and conform to the compound-reproduction arrangement and configuration.
- 80 13. The herein described improvement in toothed-gearing, it consisting in a pair of gears comprising a master-wheel provided 85 with teeth each having a pair of transversely converging working-surfaces with profiles of a conic-section contour consisting of a circular-arc and uniform throughout the length of the tooth-surface, and each surface having surface-elements in alinement with a geometric master-form-axis which coincides with the hypotenuse of a plane-triangle another side of which at a plurality of points in the length thereof, coincides with a line that is parallel to the wheel-axis, the vertex of the triangle being in the instant-axis of the gears and the plane of said triangle being oblique to and intersecting a plane through the wheel-axis 90 and said vertex, and said wheel-tooth pairs of working-surfaces conforming to the single-reproduction arrangement and configuration, in combination with a mating pinion having its axis in coöperative relation to the wheel-axis, and having wheel-engaging teeth provided with working-surfaces which are conjugate to said wheel-tooth working-surfaces and conform to the compound-reproduction arrangement and configuration.
- 95 14. The herein described improvement in toothed-gearing, it consisting in a pair of gears comprising a master-wheel provided 100 with teeth each having a pair of transversely converging working-surfaces with profiles of a conic-section contour consisting of a circular-arc and uniform throughout the length of the tooth-surface, and each surface having surface-elements in alinement with a geometric master-form-axis which coincides with the hypotenuse of a plane-triangle another side of which at a plurality of points in the length thereof, coincides with a line that is parallel to the wheel-axis, the vertex of the triangle being in the instant-axis of the gears and the plane of said triangle being oblique to and intersecting a plane through the wheel-axis 105 and said vertex, and said wheel-tooth pairs of working-surfaces conforming to the single-reproduction arrangement and configuration, in combination with a mating pinion having its axis in coöperative relation to the wheel-axis, and having wheel-engaging teeth provided with working-surfaces which are conjugate to said wheel-tooth working-surfaces and conform to the compound-reproduction arrangement and configuration.
- 110 15. The herein described improvement in toothed-gearing, it consisting in a pair of gears comprising a master-wheel provided 115 with teeth each having a pair of transversely converging working-surfaces with profiles of a conic-section contour consisting of a circular-arc and uniform throughout the length of the tooth-surface, and each surface having straight-line surface-elements in parallel with a geometric master-form-axis which coincides with the straight-line hypotenuse of a plane-triangle another side of which coincides with a line that is parallel to the wheel-axis, the vertex of the triangle being in the instant-axis of the gears and the plane of said triangle being oblique to and intersecting a plane through the wheel-axis and said vertex, and said wheel-tooth pairs of working-surfaces conforming to the single-reproduction arrangement and configuration.

of the triangle being in the instant-axis of the gears and the plane of said triangle being oblique to and intersecting a plane through the wheel-axis and said vertex, and 5 said wheel-tooth pairs of working-surfaces conforming to the single-reproduction arrangement and configuration, in combination with a mating pinion having wheel-engaging teeth provided with working-surfaces which are conjugate to said wheel-tooth working-surfaces and conform to the compound-reproduction arrangement and configuration.

14. The herein described improvement in 15 toothed-gearing, it consisting in a pair of gears comprising a master-wheel provided with teeth each having a pair of transversely converging working-surfaces with curved profiles of conic-section contour and uniform 20 throughout the length of the tooth-surface, and each surface having surface-elements in alinement with a geometric master-form-axis which coincides with the hypotenuse of a plane-triangle another side of which at 25 a plurality of points in the length thereof, coincides with a line that is parallel to the wheel-axis, the vertex of said triangle being in the instant-axis of the gears, and said wheel-tooth pairs of working-surfaces conforming to the single-reproduction arrangement and configuration, in combination with a mating pinion having its axis in co-operative 30 relation to the wheel-axis, and having wheel-engaging teeth provided with working-surfaces which are conjugate to said wheel-tooth working-surfaces and conform to the compound-reproduction arrangement and configuration.

15. The herein described improvement in 40 toothed-gearing, it consisting in a pair of gears comprising a master-wheel provided with teeth each having a pair of transversely and inwardly converging working-surfaces with profiles of conic-section curvature and uniform 45 throughout the length of the tooth-surface, and each surface having surface-elements in alinement with a geometric master-form-axis which coincides with the hypotenuse of a plane-triangle another side of which at 50 a plurality of points in the length thereof, coincides with a line that is parallel to the wheel-axis, the vertex of said triangle being in the instant-axis of the gears, and said wheel-tooth pairs of working-surfaces conforming to the single-reproduction arrangement and configuration, in combination with a mating pinion having its axis in co-operative 55 relation to the wheel-axis, and having wheel-engaging teeth provided with working-surfaces which are conjugate to said wheel-tooth working-surfaces and conform to the compound-reproduction arrangement and configuration.

16. The herein described improvement in 60 toothed-gearing, it consisting in a pair of

gears comprising a master-wheel provided with teeth each having a pair of transversely converging working-surfaces with profiles of a conic-section curvature consisting of a circular-arc and uniform throughout the 70 length of the tooth-surface, and each surface having surface-elements in alinement with a geometric master-form-axis which coincides with the hypotenuse of a plane-triangle another side of which at a plurality 75 of points in the length thereof, coincides with a line that is parallel to the wheel-axis, the vertex of said triangle being in the instant-axis of the gears, and said wheel-tooth pairs of working-surfaces conforming to the 80 single-reproduction arrangement and configuration, in combination with a mating pinion having its axis in co-operative relation to the wheel-axis, and having wheel-engaging teeth provided with working-surfaces which are conjugate to said wheel-tooth working-surfaces and conform to the compound-reproduction arrangement and configuration.

17. The herein described improvement in 90 toothed-gearing, it consisting in a pair of gears comprising a master-wheel provided with teeth each having a pair of transversely and inwardly converging working-surfaces with profiles of a conic-section 95 curvature consisting of a circular-arc and uniform throughout the length of the tooth-surface, and each surface having straight-line surface-elements in parallel with a geometric master-form-axis which coincides with the straight-line hypotenuse of a plane-triangle another side of which coincides with a line that is parallel to the wheel-axis, the vertex of the said triangle being in the instant-axis of the gears, and said wheel-tooth pairs of working-surfaces conforming to the single-reproduction arrangement and configuration, in combination with a mating pinion having its axis in co-operative relation to the wheel-axis, and having wheel-engaging teeth provided with working-surfaces which are conjugate to said wheel-tooth working-surfaces and conform to the compound-reproduction arrangement and configuration.

18. The herein described improvement in toothed-gearing, it consisting of a pair of mating gears, comprising a pinion in combination with a master-wheel provided with working-surfaces arranged in successive 120 pairs and each having the profile lines thereof curved and uniform throughout the length of the working-surface, and each pair of said working-surfaces being also transversely converging and arranged in longitudinal-parallelism and conforming to the single-reproduction configuration according with a master-form, the said wheel-teeth being each located between two adjacent said wheel-tooth working-surfaces, and said pin- 125 130

ion having the wheel-engaging tooth-surfaces thereof curved to conform to the compound-reproduction configuration according with the said wheel master-form.

5 19. The herein described improvement in toothed-gearing, it consisting of a pair of mating gears, comprising a pinion in combination with a master-wheel provided with working-surfaces arranged in successive 10 pairs and each having the profile lines thereof curved and uniform throughout the length of the working-surface, and each pair of said working-surfaces being also transversely and inwardly converging and arranged in longitudinal-parallelism and conforming to the single-reproduction configuration according with a master-form, the said wheel-teeth being each located between two adjacent said wheel-tooth working-surfaces, and said pinion having the wheel-engaging tooth-surfaces thereof curved to conform to the compound-reproduction configuration according with the said wheel master-form.

25 20. The herein described improvement in skew gearing, it consisting in a pair of conical gear wheels comprising a master wheel provided with teeth having working surfaces, each of which is of uniform curved 30 profile throughout its length, the working surfaces of which are conjugate to the respective working surfaces of the teeth of the mating wheel of the pair.

21. The herein described improvement in toothed gearing, it consisting in a pair of gears comprising a master wheel provided with teeth each having a working surface with uniform profiles throughout the length thereof and each surface having surface-elements parallel to a geometric master-form-axis which coincides with the hypotenuse of a plane triangle another side of which coincides with a line lying in a plane passing through the wheel axis, the vertex 45 of said triangle being in the instant axis of the gears, and said wheel-tooth working surfaces conforming to the single-reproduction configuration, in combination with a mating pinion having its axis in co-operative relation to the wheel axis, and have wheel-engaging teeth each provided with a working-surface conjugate to said wheel-tooth working-surface and conforming to the compound-reproduction configuration.

55 22. The herein described improvement in toothed-gearing, it consisting of a pair of mating gears, comprising a pinion in combination with a master-wheel provided with working-surfaces arranged in successive 60 pairs and each having the profile lines thereof uniform throughout the length of the working-surface, and each pair of said working-surfaces being arranged in longitudinal parallelism and conforming to the single-reproduction configuration according

to a master-form, and said pinion having the wheel-engaging tooth-surfaces thereof conforming to the compound-reproduction configuration according with the said wheel master-form.

23. The herein described improvement in toothed-gearing, it consisting of a pair of gears comprising a master wheel provided with teeth each having a pair of transversely converging working-surfaces, of which each 75 surface has longitudinal surface-elements in parallel with a geometric master-form axis which coincides with the hypotenuse of a plane-triangle, another side of which at a plurality of points in its length coincides with a line lying in a geometric plane passing through the wheel axis, the vertex of said triangle being in the instant axis of said gears, the working surfaces of each wheel tooth pair being arranged in parallel relation 80 to each other and conforming to the single-reproduction arrangement and configuration, in combination with a mating pinion having wheel engaging teeth provided with pairs of working surfaces which are conjugate to said wheel tooth working surface and conforming to the compound-reproduction arrangement and configuration.

24. A pinion having wheel-engaging teeth each provided with working-surfaces conforming to the compound-reproduction configuration and conjugate to wheel tooth working surfaces of uniform profile throughout the length thereof and each such latter working-surfaces having surface elements 95 parallel with a geometric master-form-axis which coincides with the hypotenuse of a plane-triangle another side of which, at a plurality of points in the length thereof coincides with a line lying in a geometric 100 plane passing through such wheel axis, the vertex of said triangle being in the instant axis of the gears, and said wheel tooth working-surfaces conforming to the single-reproduction configuration.

25. The herein described improvement in toothed-gearing, it consisting in a pair of gears comprising a master wheel provided with teeth each having a pair of working-surfaces with profiles of conic-section contour and uniform throughout the length of the tooth surface, and each surface having surface elements parallel with each other and with a geometric master-form axis which coincides with the hypotenuse of a 115 plane triangle another side of which at a plurality of points in the length thereof coincides with a line lying in a plane passing through the wheel-axis, the vertex of said triangle being in the instant-axis of the 120 gears, and said wheel tooth working surfaces conforming to the single-reproduction arrangement and configuration, in combination with a mating pinion having wheel engaging teeth provided with working-surfaces 130

faces which are conjugate to said wheel-tooth working-surfaces and conform to the compound-reproduction arrangement and configuration.

- 5 26. The herein described improvements in toothed-gearing, it consisting in a pair of gears comprising a master-wheel provided with teeth each having a pair of working-surfaces with profiles of circular-arc contour 10 and uniform throughout the length of the tooth surface, and each surface having surface elements parallel with each other and with a geometric master-form-axis which coincides with the hypotenuse of a plane triangle another side of which at a plurality of points in the length thereof coincides with a line lying in a plane passing through the wheel-axis, the vertex of said triangle being in the instant-axis of the gears, and said 15 wheel tooth working surfaces conforming to the single-reproduction arrangement and configuration, in combination with a mating pinion having wheel engaging teeth provided with working-surfaces which are conjugate to said wheel-tooth working-surfaces and conform to the compound-reproduction arrangement and configuration.
- 20 27. A pair of mating gears, consisting of a toothed skew wheel having working tooth-surfaces of single-reproduction configuration, and a toothed pinion having working tooth-surfaces of compound-reproduction configuration conjugate to the tooth surfaces of said wheel.
- 25 28. A pair of mating gears, consisting of a toothed skew wheel having working tooth-surfaces free from longitudinal twist, and a

pinion having longitudinally-twisted working tooth-surfaces conjugate to the working tooth-surfaces of said wheel.

29. A pair of mating bevel gears, consisting of a skew bevel wheel having working tooth-surfaces free from longitudinal twist, and oblique with reference to the axis of said wheel, and a bevel pinion having longitudinally-twisted working tooth-surfaces conjugate to the skew tooth-surfaces of said wheel.

30. A toothed wheel having working tooth-surfaces arranged in consecutive pairs, 50 each of said tooth-surfaces being composed of parallel longitudinal line-elements, the line-elements of the two tooth-surfaces of the same pair being parallel to one another, but oblique with reference to the longitudinal line-elements of the adjacent pairs.

31. A pair of mating gears, consisting of a wheel having working tooth-surfaces arranged in consecutive pairs, each of said tooth-surfaces being composed of parallel 60 longitudinal line-elements, the line-elements of the two tooth-surfaces of the same pair being parallel to one another, but not to the line-elements of the adjacent pairs, the line-elements of said tooth-surfaces being oblique 65 with reference to the axis of the wheel, and a pinion having working tooth-surfaces arranged in consecutive pairs and conjugate to those of said wheel.
